(57) **CLAIM**

The ornamental design for a hot air comb, as shown.

DESCRIPTION

FIG. 1 is a front elevational view of a hot air comb showing my new design;

FIG. 2 is a rear elevational view thereof;

FIG. 3 is a left side view thereof;

FIG. 4 is a right side view thereof;

FIG. 5 is an enlarged top plan view thereof;

FIG. 6 is an enlarged bottom plan view thereof;

FIG. 7 is a perspective view thereof;

FIG. 8 is a second perspective view thereof;

FIG. 9 is a third perspective view thereof;

FIG. 10 is an enlarged fourth perspective view thereof;

FIG. 11 is an enlarged fifth perspective view thereof; and,

FIG. 12 is an enlarged sixth perspective view thereof.
